UNITED STATES PATENT OFFICE.

JOHN W. SIDEBOTTOM, OF LOWELL, MASSACHUSETTS, ASSIGNOR TO T. C. ENTWISTLE COMPANY, OF LOWELL, MASSACHUSETTS, A CORPORATION OF MASSACHUSETTS.

LEASE-FORMER.

1,109,257.

Specification of Letters Patent.

Patented Sept. 1, 1914.

Application filed January 16, 1913. Serial No. 742,451.

To all whom it may concern:

Be it known that I, JOHN W. SIDEBOTTOM, of Lowell, in the county of Middlesex and the Commonwealth of Massachusetts, have invented certain new and useful Improvements in Lease-Formers, of which the following description, with the accompanying drawing, is a specification.

This invention relates to Lease-Formers and to lease-combs having a dent having an eye for carrying a thread sometimes above and sometimes below another thread.

The invention lies in the construction of a dent having a spiral-eye and in its combination with other parts, as is set forth in the claims.

In the drawing, which represents my invention in the preferred form: Figure 1 is a partial elevation looking laterally of the comb. Figs. 2, 3, and 4 are partial elevations looking longitudinally of the comb and showing the comb in its highest, middle, and lowest positions, respectively. Fig. 5 is an elevation of a detail looking in a direction which is the opposite to that of Figs. 2, 3, and 4. Fig. 6 is an elevation of a detail corresponding in direction with Fig. 1. Fig. 7 is a cross-section taken at line 7—7 of Fig. 6. Fig. 8 is a cross-section taken at line 8—8 of Fig. 6.

In the drawing, 1 and 1 are stationary brackets secured to the framing (not shown) of a lease-warper. Each bracket has a vertical slot 2, the front and rear side walls of which guide the comb-box 3 as it moves up and down. Stops 4 are fastened to the box and sliding up and down alongside the brackets serve through engagement with the sides of the latter to prevent endwise movement of the box. The box extends beyond the brackets and is supported at both ends by wedge-shaped cams 5 connected together by a rod 6 to which they are set-screwed to make them fast therewith. One of the cams has a handle 7 and both can be moved by it lengthwise of the box. Each cam has a smooth horizontal top face 8 upon which the box rests. The said face touches the lower horizontal face of the box and can slide beneath it. It has upon its lower side three rests 9, 10, and 11 for contact with a support 12 constituted by the bottom portion of the bracket. The inclined faces 13 and 14 connect the rests and slide upon the support 12 during the motions of the cam.

Horizontal motions of the cams cause vertical motions of the box. The different vertical positions of the comb are shown in the drawings, viz: in Figs 1 and 2, in the highest position, as when the rests 9 are on the supports 12; in Fig. 3 in the position of intermediate height, as when the rests 10 are on those supports; and in Fig. 4 in the lowest position, as when the rests 11 are on them. The comb has the springs 15 and other usual appurtenances of an expansion comb operating to hold its dents from turning or rotating. Supported between the coils of the springs, in usual manner, are flat-wire dents 16 alternating with dents 17 of my invention. Each dent 17 has a body 18 of flat-wire which is identically like a dent 16. Soldered to this body at a distance from its top end greater than the distance to which the two planes of threads of a lease are separated vertically in forming a lease; that is to say, at a distance from said end greater than the depth of a lease-shed, is a "pig-tail" or spiral-eye 19 made from round-wire. The body combined with the spiral-eye constitutes the dent 17. Each spiral-eye has ascending and descending portions 20 and 21 that are laterally offset from the shank toward the front of the comb, the portion 20 being laterally opposite the body 18 and the portion 21 being, substantially, laterally opposite to a dent 16. The extremity 29 of the outer coil of the eye follows the adjoining coil out of a vertical direction and away from the space 24 between dents 16 and 17 to prevent a thread in the space 24 from being caught upon it. It is then given a short upward turn to facilitate the threading of the eye, as will be made apparent later herein. It is not essential that the dent 16 and the body 18 shall be of flat-wire or identical; that the spiral-eyes shall be made from round-wire; or, that the dent 17 shall be constructed by uniting two separate pieces of metal.

In threading the warper, one half of the threads 22 are each twisted into the eye of a drop-wire 23 and dropped into a space 24 between a dent 16 and a dent 17 where there is no spiral-eye. They are then led over the roll 25 to the thread-receiver (not shown). These threads 22 are not influenced by motions of the comb. They need not be moved while taking a lease. The other half of the threads 26 are each twisted into the eye of a

drop-wire 27, dropped into a space 28 between a dent 16 and a dent 17 where a spiral-eye 19 is located, carried down past the spiral eye at the free or unattached side of the latter, then carried laterally beneath the spiral eye, then carried up between the attached extremity of the eye and the free extremity and laterally over its end 29 and down into its interior, and then led over the roll 25 to the thread-receiver.

For the usual operation of warping the parts are given the positions of Fig. 3 with the cams and the comb in their middle positions. In taking a lease, the comb-box is moved alternately into the position of Fig. 2 and that of Fig. 4, and the lease-threads are inserted in the open sheds shown in Figs. 2 and 4 between the dents and the roll 25. To obtain the positions of Fig. 2 the cams are moved to their extreme right positions in Fig. 1. This carries the threads 26 above the threads 22. To obtain the positions of Fig. 4 the cams are moved to their extreme left positions in Fig. 1. This carries the threads 26 below the threads 22, but the plain upper portions of the dents 16 and 17 above the spiral eyes are of ample length to permit the comb-box to be lowered as in Fig. 4 without withdrawing the said upper portions from between the threads of the upper plane of the lease-shed. By reason of the fact that the free extremity of the "spiral-eye" is bent from the side of the eye toward the middle of the width of the latter, as represented clearly in Figs. 1, 6 and 7, it follows that as the comb is raised and lowered and the spiral-eyes pass up and down between the threads occupying the alternating dent-spaces, in shifting from the position shown in Fig. 4 to that shown in Fig. 2 and vice versa, there is no danger of the said free extremity catching one of the latter threads. The form and construction of the spiral-eye are such as to prevent the threads on either side of the same from getting into the eye in taking the lease. On reference to Figs. 1 and 6 it will be observed that the dents of the comb are alternately long and short, and that the spiral-eyes respectively are mounted upon the long dents. The difference in the lengths of the dents indicates to the operator which dents have the spiral-eyes, so that the operator will not have to look so long in putting the threads down into the comb-spaces and into the eyes.

Relative to lease-combs of the prior art which are adapted for both elevating and depressing one set of threads with respect to another set of threads, it is thought that the lease-comb of this invention is superior to any of the prior art in that it is stronger, more durable, and less expensive to manufacture than any prior lease-comb which is so great a saver of labor in drawing-in a warp.

I claim:

1. In a lease-comb, a dent having at an intermediate point in its height a spiral-eye for a thread and having above said eye a plain upward extension exceeding in length 70 the depth of a lease-shed.
2. In a lease-comb, a flat dent having affixed thereto a spiral-eye of round wire.
3. In a lease-comb, a dent having a flat shank and having a spiral-eye. 75
4. In a lease-comb, a dent having at an intermediate point in its height a spiral-eye having ascending and descending portions that are laterally offset from the shank.
5. In a lease-comb, a dent having at an 80 intermediate point in its height a spiral-eye having ascending and descending portions that are laterally offset from the shank, one such portion being in the lateral projection of its shank upwardly extended. 85
6. In a lease-comb, a dent having at an intermediate point in its height a spiral-eye of which the free extremity of the outer coil follows the adjoining coil out of a vertical direction and then projects above it. 90
7. In a lease-comb, a dent having an outstanding spiral-eye in combination with means for preventing its rotation.
8. In a lease-comb having spiral-springs, the combination with the springs of dents 95 each having an outstanding spiral-eye and having means for preventing the rotation of the dent located between the coils of the springs.
9. The combination of a lease-comb box 100 provided with dents each having at an intermediate point in its height a spiral-eye and each having also above said eye a plain upward extension exceeding in length the depth of a lease-shed, with the spaces between 105 dents open at their upper ends to permit the threads to be dropped into the same, with means for holding the box at different heights.
10. The combination of a lease-comb box, 110 spiral springs located within the box, and flat dents alternating with dents each having a flat shank and a spiral-eye, the shanks of the dents located between the coils of the springs, with the spiral-eye located at an intermediate point in the height of its dent and with a plain upward extension above said eye exceeding in length the depth of a lease-shed, the spaces between dents being open at their upper ends to permit the 115 threads to be dropped into the same. 120
11. The combination of a lease-comb having dents respectively provided at an intermediate point in the height thereof with a spiral-eye, and cams adapted for movement 125 lengthwise of the comb to change its elevation for forming a lease, each of said dents having above its spiral-eye a plain upward extension exceeding in length the depth of a lease-shed, the spaces between dents being 130

open at their upper ends to permit the threads to be dropped into the same.

12. A lease-comb comprising a series of plain flat dents alternating with dents each having a spiral-eye located at an intermediate point in the height of the dent and a plain upward extension above said eye exceeding in length the depth of a lease-shed, the spaces between dents being open at their upper ends to permit the threads to be dropped into the same.

13. A lease-comb comprising a series of flat dents alternating with dents each having at an intermediate point an outstanding spiral-eye having ascending and descend-

ing portions that are laterally offset from the shank, one such portion being substantially in the same plane with the body of the dent, and the dents having above said eyes plain upward extensions exceeding in length 20 the depth of a lease-shed, the spaces between dents being open at their upper ends to permit threads to be dropped into the same.

In testimony thereof, I affix my signature in the presence of two witnesses.

JOHN W. SIDEBOTTOM.
